UNITED STATES PATENT OFFICE.

JOHN T. RIDDELL, OF EVANSTON, ILLINOIS.

ATHLETIC SHOE.

Application filed December 29, 1926. Serial No. 157,666.

This invention relates to improvements in shoes of the type in which friction devices are added to the soles for preventing slipping under stress.

5 The primary object in view is the simple, inexpensive, and efficient anchorage of cleats to shoe soles.

With this and further objects in view, as will in part hereinafter become apparent 10 and in part be stated, the invention comprises certain novel constructions, combinations, and arrangements of parts, as subsequently specified and hereafter set forth in the appended claims.

15 In the accompanying drawing,

Fig. 1 is an inverted plan view of a shoe sole, embodying features of the present invention;

Fig. 2 is a top plan view of the same;

20 Fig. 3 is an edge view of the same;

Fig. 4 is an enlarged, detailed, vertical section through the sole, on a plane of the axes of one of the cleats, the cleat and its retaining screw being seen in elevation;

25 Fig. 5 is a sectional elevation of one of the cleats detached, the cleat being shown in full lines prior to its application and in dotted lines after application;

Fig. 6 is a section on the plane indicated 30 by line 6-6 of Fig. 2.

Referring to the drawing by numerals, 1 indicates the sole of a shoe, to the tread and heel portions of which is secured a number 35 of friction cleats, each consisting of an exposed truncated cone 2, having a reduced shank 3 upstanding into the sole 1. Sole 1 is formed with aperture 4, one for each of said cleats, each aperture being proportioned to snugly receive a shank 3. The formation 40 of shank 3 leaves a circular shoulder 5 at the base of the cone 2, which shoulder outstands beyond the line of the aperture 4 and rests against the under face of sole 1. Said shoulder 5, therefore, receives most of 45 the reactive stresses incident to walking upon the cleats, and delivers same directly to the sole 1, through which they are distributed substantially uniformly to the foot of the wearer. Each of said cleats, before 50 anchorage in the sole, is formed with an axial bore 6 which terminates a considerable distance short of the lower end of the cone 2. The cleat made up of the cone 2 and shank 3 is preferably formed of rubber of

the somewhat hardened type commonly utilized for cleats of athletic shoes. The degree of vulcanization or hardening does not extend to the point of rendering the cleat non-elastic. It does, however, extend sufficiently for rendering the cleat strong and wear res- 55
isting. A screw 7 anchors each cleat 2 in place. Each screw 7 is formed with a high pitched or wide angled tapering thread 8 of the type commonly employed on iron screws used in wood, and known commonly as wood 60 screws. Screw 7, however, differs from an ordinary wood screw in three respects. It is provided with a head 9 of relatively wide area and preferably circular in form, it is truncated and has a flat entering end, and 65 it is case hardened. The head 9 is provided with openings 10-10, adapted to receive the shanks of a spanner wrench for facilitating rotation of the screw in threading it into the bore 6 after the shank 3 has been seated 70 snugly within aperture 4. The outer terminus 11 of the screw 7, as clearly seen in Figures 6 and 7 is flat, the screw being truncated to present a flat surface to the material at the base of bore 6. Thread 8 75 remains the full width to the outer terminus of the screw. Bore 6, before anchorage of the cleat, is preferably cylindrical and of less diameter than the root diameter of the screw 7 at its smallest cross section. 80

In mounting the cleats, the sole 1 is provided with the requisite number of apertures 4, and the shanks 3 are introduced therein until the several cleats are all set with the shoulders 5 resting against the under surface of the sole 1. Screw 7 is then inserted from the upper or inside of the sole and screwed in shank 3 along and within bore 6 until the parts are firmly clamped together. In moving to this position the screw and cleat assume the relative condition indicated in Figure 6. As the root diameter of the screw 7 is somewhat tapered and of greater diameter than the bore 6, the screw in passing down the bore, will cause 85 the threads 8 to enter the material of shank 3, and the body of the screw crowds such material with a wedging action radiating in all directions, swelling or tending to swell the shank into a firmly seated condition 90 against the surrounding walls of aperture 4, the material of the shank along the bore 6 filling the valleys or grooves between the 95
100

several helixes of the thread 8, and, thus, effecting a firm and reliable anchorage to the cleat.

A shoe supplied with cleats of the character shown and described is especially well adapted for players of golf or other outdoor sportsmen particularly desirous of obtaining a good foothold when required, without going to the extreme of the use of the larger 10 cleats commonly employed for foot ball shoes and the like.

However, the invention is in no sense limited to the particular use nor the exact size of the cleat employed. All cleats within the 15 range of successful use of whatever size are included within the scope and intent of the invention so long as utilizing the features thereof.

What is claimed is:

20 1. The combination, with a shoe sole having an aperture, of a cleat of readily expandible material having a shank adapted to snugly fit said aperture, the shank being formed with a longitudinal bore, and a screw 25 of larger root diameter than said bore, threaded into the bore from the inner portion of the sole.

2. The combination, with a shoe sole having an aperture, of an elastic hardened rubber cleat having a shank proportioned to snugly fit within the aperture of the sole, the cleat outside the sole being of larger diameter than the shank and formed with a shoulder outstanding from the shank and resting 35 against the under surface of the sole, and anchoring means extending from the inner portion of the sole and engaging said shank for causing said shank to spread into firm engagement with the inner surface of said 40 aperture.

3. The combination, with a shoe sole having an aperture, of an elastic hardened rubber cleat having a shank proportioned to snugly fit within the aperture of the sole, 45 the cleat outside the sole being of larger diameter than the shank, the shank being formed with a longitudinal bore, and a screw threaded into said bore from the interior portion of the sole and spreading said bore 50 and causing said shank to firmly engage the inner surface of said aperture.

4. The combination, with a shoe sole having an aperture, of an elastic hardened rubber cleat, having a shank proportioned to snugly fit within the aperture of the sole, the 55 cleat outside the sole being of larger diameter than the shank, the shank being formed with a longitudinal bore, and a screw having a larger root diameter than the diameter of said bore threaded into said bore from the 60 interior portion of the sole.

5. The combination, with a shoe sole having an aperture, of a cleat of readily expandible material having a shank fitted in said aperture, and a tapered, case hardened screw, having a truncated body and flat outer end and a wide angle thread, threaded into said shank from the inner portion of the sole. 65

6. In combination with a shoe sole provided with a hole, a vulcanized rubber cleat having a shank for reception into the hole in said shoe sole, a cylindrical bore within the shank, said shank having a shouldered portion protruded exteriorly through said sole, said shouldered portion having the configuration of the frustum of a cone, the truncated portion of which contacts directly with the ground, a truncated screw having a flattened head providing an integral disc for seating on the inner side of said sole when 70 said screw is threaded into said cylindrical bore, the shoe sole being clamped firmly between the flattened head of the screw and the exterior shouldered portion of the shank 75 when said screw is threaded into said cylindrical bore. 80

7. In combination with a shoe sole provided with a hole, a cleat of readily expandible material having a shank portion adapted to fit snugly into said hole, said cleat having an enlarged portion adapted to extend below the tread surface of said sole and provided with a shoulder portion adapted to engage the surface of the sole, a bore within 90 said cleat shank, and a screw provided with a flattened head, said head being of greater area than said hole and disposed upon the upper side of said sole, said screw adapted to be threaded into said bore. 95

In testimony whereof I have signed my 100 name to this specification.

JOHN T. RIDDELL.
